The ornamental design for a rotary tool holder, as shown and described.

DESCRIPTION

FIG. 1 is a front perspective view of a rotary tool holder with a bit and the drive shank shown in shadow; FIG. 2 is a front perspective view of the rotary tool holder; FIG. 3 is a right side view of the rotary tool holder with the left side view being a mirror image thereof; FIG. 4 is a front view thereof; FIG. 5 is a rear view thereof; and,

FIG. 6 is a side view of a second embodiment of the rotary tool holder.

The broken line showing of the tool bit and the drive shank are for illustrative purposes only and form no part of the claimed design.

The second embodiment of the rotary tool holder shown in FIG. 6 is identical to the first embodiment of the rotary tool holder shown in FIGS. 1-5 in all respects except for the elimination of the “knurling” as illustrated.
